UNITED STATES PATENT OFFICE.

JOHN IRVINE, OF PHILADELPHIA, PENNSYLVANIA.

HANGER.

1,074,623.

Specification of Letters Patent.

Patented Oct. 7, 1913.

Application filed April 18, 1913. Serial No. 761,868.

To all whom it may concern:

Be it known that I, JOHN IRVINE, a citizen of the United States, residing at Philadelphia, in the county of Philadelphia and 5 State of Pennsylvania, have invented certain new and useful Improvements in Hangers, of which the following is a specification.

My invention relates to improvements in 10 hangers, the object of the invention being to provide an improved hanger composed of a single piece of spring wire bent forming a plurality of garment supporting hooks and an article clamp.

15 A further object is to provide a hanger of this character which may be rigidly secured in position by the employment of a single screw or other similar holding device, and which will be extremely simple in construction, neat and attractive in appearance, and 20 strong and durable in use.

With these and other objects in view, the 25 invention consists in certain novel features of construction and combinations and arrangements of parts as will be more fully hereinafter described and pointed out in the claims.

In the accompanying drawings: Figure 1 30 is a perspective view illustrating my improvements, showing the same supporting a cane or umbrella handle, the latter being illustrated in dotted lines, and Fig. 2 is a plan view of the hanger.

My improved hanger comprises a single 35 piece of relatively heavy spring wire which is bent centrally between its ends forming a vertical eye 1 which is adapted to receive a screw, nail, or other device (not shown) to rigidly secure the hanger to a wall or 40 similar support.

The ends of the wire at the base of the eye 1 are crossed and project in opposite directions for a short distance as shown at 2, and both ends are coiled as shown at 4. 45 While of course the number of convolutions is immaterial, yet I preferably provide at least two, and said convolutions located at right angles to the eye 1 or otherwise horizontal when the eye 1 is positioned vertically.

The ends of the coils 4, which are at the base thereof, extend diagonally toward each other as shown at 5 and are then bent at an acute angle, although the bend is some- 55 what round as indicated at 6.

The two ends of the wires 6 extend in opposite directions and in alinement as shown at 7 and are bent upwardly and then downwardly forming rounded hooks 8. The ends of the wires then extend toward each other in alinement, and parallel with the portion 7 as indicated at 9, and at their free ends are curved outwardly and backwardly as shown at 10 forming an entrance which has curved walls. 60

65 The extreme ends of the wires are bent upwardly forming hooks 11. With my improvements, the ends 8 and 11 constitute effectual supports for clothing and other articles, and the four curves or bends 6 and 10 constitute a clamp preferably for an umbrella or cane handle 12, when the latter is forced between the curves 10 into the position indicated in dotted lines in Fig. 1.

70 It will be noted that the coils 4 are at opposite sides of the eye 1, and have their inner walls preferably in the same vertical plane, so that they form an additional support against the wall, and the coils 4, 4, will open to compensate for the weight of articles on the several hooks without bending the hanger. 75

80 Various slight changes might be made in the general form and arrangement of parts 85 described without departing from my invention, and hence I do not limit myself to the precise details set forth, but consider myself at liberty to make such changes and alterations as fairly fall within the spirit and scope of the appended claims. 90

Having thus described my invention, what I claim as new and desire to secure by Letters Patent is:

1. A hanger of the character described, 95 comprising a single piece of spring wire having its intermediate portion bent into circular form with the ends of the wires crossed forming an eye, coils formed in the wire at opposite sides of the eye, the ends of the wires then projecting inwardly toward each other, and then outwardly in opposite directions, then curved upwardly, then extended toward each other substantially in parallelism with the outwardly bent portion, then curved outwardly and upwardly forming a clamp having four contact points and having a curved entrance thereto, substantially as described. 100

105 2. A hanger of the character described, comprising a single piece of spring wire 110

having its intermediate portion bent into circular form with the ends of the wires crossed forming an eye, coils formed in the wire at opposite sides of the eye, said coils having their inner edges in substantially the same vertical plane as the eye, the ends of the wires then projecting inwardly toward each other and then outwardly in opposite directions, then curved upwardly, then extended toward each other substantially in parallelism with the outwardly bent portion, then curved outwardly and upwardly forming a clamp having four contact points and having a curved entrance thereto, substantially as described.

3. A hanger of the character described, comprising a single piece of spring wire bent between its ends forming an eye, coils at opposite sides of the eye, said wire bent at its ends forming four hangers, and a spring clamp, said spring clamp having four

contact points and a relatively wide entrance, substantially as described.

4. A hanger of the character described, comprising a single piece of wire bent between its ends forming an eye, coils at opposite sides of the eye, arms projecting in opposite directions and each comprising two parallel sections of wire, the inner ends of said sections spaced apart whereby an article 25 clamp is formed having four contact points, and the ends of the wire flared apart forming an entrance to said clamp, substantially as described.

In testimony whereof I have signed my 35 name to this specification in the presence of two subscribing witnesses.

JOHN IRVINE.
